UNITED STATES PATENT OFFICE.

PAUL GENESY, OF OGDEN, UTAH, ASSIGNOR, BY DIRECT AND MESNE ASSIGNMENTS,
TO GENESY ELECTRIC LANTERN COMPANY, A CORPORATION OF WYOMING.

RAILROAD LANTERN.

1,410,671.

Specification of Letters Patent. Patented Mar. 28, 1922.

Application filed March 30, 1921. Serial No. 457,005.

To all whom it may concern:

Be it known that I, PAUL GENESY, a citizen of the United States, residing at Ogden, in the county of Weber and State of Utah, 5 have invented certain new and useful Improvements in Railroad Lanterns, of which the following is a specification, reference being had to the accompanying drawings.

This invention relates to lanterns, and 10 particularly to lanterns of the type used by conductors, brakemen and trainmen generally on railways, and the general object of the invention is to provide a lantern which will stand a lot of hard usage, which is designed to be illuminated by an electric light 15 energized from the ordinary dry battery, and which is extremely simple.

A further object is to provide a lantern 20 of this character so constructed that the light is thrown downward when the body of the lantern is not lifted to a horizontal position.

And a further object is to provide a construction of this character wherein a very 25 simple form of switch is provided to connect or disconnect the battery with the lamp.

Another object is to provide for the use 30 of a light condensing lens operating in conjunction with the reflector and the lamp, which lens is adjustable to alter its focus.

Other objects have to do with the details 35 of construction and arrangement of parts as will appear in the course of the following description.

My invention is illustrated in the accompanying drawings, wherein:—

Figure 1 is a side elevation partly in section of one form of my improved lantern;

Figure 2 is a section on the line 2—2 of 40 Figure 1;

Figure 3 is a top plan view of the annular member 30 of insulating material;

Figure 4 is a section on the line 4—4 of 45 Figure 1;

Figure 5 is a fragmentary elevation of the lower portion of another embodiment of my invention;

Figure 6 is a fragmentary section of the lower portion of a lantern embodying an 50 other form of my invention;

Figure 7 is a sectional view of the lower end of the body 10 looking downward.

Referring to these drawings and particularly to Figures 1 to 4, 10 designates the body of the lantern, which is made in the 55 form of a cylindrical battery receiving receptacle closed by a hinged lid 11 at its upper end. Riveted or otherwise attached to the body 10 at opposite points are the handle sockets 12, and engaged in said handle sockets is a handle 13 which, is preferably of wood and arches over the top of the lamp.

The lower end of the body 10 is permanently closed by a head 14, the central portion of this head being concave, as at 15, 60 to provide a reflector, and at the central portion of this reflector there is provided a lamp socket 16 designed to receive within it the base 17 of the lamp 18. Attached to the lower end of the body in any suitable manner are a plurality of outwardly and downwardly extending legs 19 connected by a bracing ring 20 which forms a base upon which the lamp may rest when it is set down. Disposed below the lamp 18 is a lens 21 65 illustrated as a plano-convex lens mounted in a supporting ring 22, and extending from the bottom of the lamp body 10 are rods 23, illustrated as two in number, though more may be used, which pass through the ring 22 70 and with which said ring 22 has sliding engagement. The ring 22 is frictionally held in engagement with these rods by means of a semi-circular spring 24 disposed within a groove 25 formed in the ring, this spring being attached at its middle to the ring, as by soldering. The lower ends of the rods 23 are angularly bent or otherwise formed to provide heads 26 to limit the outward movement of the lens.

Mounted within the body is a metallic disk 27 formed with downwardly projecting legs 28, these legs being angularly bent to provide screw-threaded feet 29 which bear against the inner face of the bottom 14 and 95 are attached thereto by screws. This member 27 is formed to provide the screw-threaded lamp socket 16. Pivotal mounted upon the upper face of this supporting disk 27 is a relatively small metallic annular disk 100

30 which is pivoted at 31 to the disk 27. Disposed upon the top of this disk 30 is a fiber insulating disk 32, and resting upon this fiber insulating disk is a central metallic 5 disk 33. The disk 30 is provided with the outwardly projecting switch handle 34 extending beneath a strap 35 attached to the supporting disk 27 and extending out through a slot 36 formed in the wall of the 10 body 10. A metallic stud 37 extends through the disks 30, 32 and 33 and forms a metallic connection between the disk 30 and the disk 33.

When this stud 37 is in its central position, 15 it contacts with the centrally disposed electrode of the lamp 18. When, however, the disk 30 is shifted by its handle, this stud 37 is carried out of its engagement with the electrode and as a consequence circuit through 20 the lamp is broken. Disposed within the body 10 is a battery of suitable construction, designated generally 38, and having on its under face the contacts 39 and 40. The contact 39 fits against the fixed disk 27, while 25 the contact 40 is adapted to engage with the stud 37 when the latter is in its centrally disposed position. When the stud 37 is in contact with the resilient contact spring 40, current will pass from the battery to stud 37, 30 thence to the filament of the lamp, thence to the outer electrode of the lamp, thence to the lamp socket and by the supporting disk 27 to the contact 39, thus completing the circuit through the lamp. When the 35 handle 34 is shifted, however, the circuit through the lamp is broken in an obvious manner.

The reflector 15 throws the light of the lamp downward and the lens 21 focuses this 40 light at distances which depend upon the adjustment of the lens. When the lens is in one position, it will focus the light of the lamp at one distance from the lamp itself, and when it is shifted it will change the focus 45 of the lamp and the light will be thrown in the form of a spot onto the body which it is desired to illuminate. The guard formed by the legs 19 and the ring 20, while it supports the lamp in position so that the light 50 is all thrown downward, does not throw any shadow on the face of the user. The switch has no wire connections, it will be seen, and therefore nothing which can get out of order. The whole weight of the lamp, including the 55 dry battery, is approximately two pounds. It will be seen that it is particularly convenient for pouring the light downward onto an object which it is desired to fully illuminate and that the light may be focused on 60 this object so as to secure full illumination thereof, which is not possible where the light of the lamp is diffused and where no focusing lens is used.

In Figure 5 I show a modified form of the 65 lower portion of the lamp wherein the lens,

which is designated in Figure 5 as 21^a, is held in fixed relation to the lamp 18^a, the lens being supported in a supporting frame designated 41. The wire guard is constructed in the usual manner, as is the switch and the 70 rest of the mechanism.

In Figure 6 I show another form of my device, wherein two lamps are used which may be of different colors or of the same color as desired, and wherein a switch is movable 75 to illuminate either lamp. In this case, the lower end of the casing 10^a is formed with two reflecting depressions 15^a, each of them provided with a socket 16^a for the lamp 18^b. The base is formed with the guard parts 80 19 and 20, as heretofore described, and with the usual handle. The only difference between this construction and the one previously described is the switch which is designed to cause the illumination of one lamp 85 or the other as may be desired. As illustrated, this switch comprises a fiber or other disk of insulating material, designated 42, to which a handle 43 is attached. Extending out through the slot 36^a in the side wall 90 of the body and attached to the upper face of this disk is a central metallic disk 44 and an annular concentric disk 45. A screw 46 forms a pivot for the combined disks 42, 44 and 45, this screw having screw-threaded 95 engagement with the bottom of the body 10. A pair of studs 47 and 48 extend down from the annular member 45 to the under face of the fiber disk 48 and are adapted to contact with the respective lamp plugs 17^a as the 100 switch is turned by its handle 43 into one position or the other. A lens 21^b is mounted in connection with the white light 18^b, this lens operating in the same manner as the lens heretofore described.

It is obvious that the switch might be arranged to cause the energizing of both lamps at a time or, as illustrated, to only energize one lamp at a time. In the latter case, the middle position of the handle 43 indicates 110 that the switch is off and neither lamp is energized, while when the handle is shifted in one direction one of the lamps is energized, and when shifted in the other direction from its middle position the other lamp is energized. It will be obvious that the principle of construction of the switch is the same as that previously described.

It will be seen that all forms of this invention are particularly adapted for railway 120 work and particularly to hand lanterns carried by conductors, trainmen or the like.

A lantern constructed in accordance with my invention will permit trainmen to make thorough inspection of trains and can also 125 be used with advantage by car checkers and conductors checking trains. The form of lantern illustrated in Figure 1 is particularly advantageous inasmuch as the lens can be adjusted to throw a light several car lengths 130

and enable the trainman to see when they are shoving the cars to a coupling. This lens will also throw a light far enough to enable trainmen working in a yard to locate 5 any obstruction that might cause them injury, or locate cars that might be projecting out over the fouling point or end of tracks. A further advantage of lanterns constructed in accordance with my invention is that the 10 light is so arranged within the reflector bowl that it does not blind the user or other men working nearby, but is directed to the point desired by the lens.

Furthermore, there are no shadows from 15 the guard 19 and ring 20 upon the object toward which the light is directed. Thus, for instance, if the user were checking up a string of cars there would be no dark shadows in the range of light, thus giving the 20 user a clear light to read the numbers and initials of the cars or otherwise. It will be noted also that the lens does not in any way interfere with the giving of signals, while at the same time it permits the lens to act 25 as a spotlight so that the user has a combined signal lantern and spotlight.

In the construction illustrated in Figure 6, the lantern secures the use of two lights so that in case one should go out the other 30 is capable of use (assuming, of course, that both lamps are white). Of course, where one lamp is white and the other red, it is to provide a lantern which can be used for ordinary purposes and also as a signal lantern. At this time all railway flagmen or 35 others acting as flagmen carry two lanterns, one red and one clear. By my construction, I provide an electric lantern which, as before stated, can be used either for flagging purposes or for ordinary purposes. It may 40 also be used for railway crossing flagmen, who ordinarily carry two oil lanterns, one green and the other red, and the lantern in Figure 6 may be used for displaying either 45 a red light or a green light. Furthermore, a red electric light is much more plainly seen by an engineer than a red light in an oil lantern.

The object of having the two reflector 50 bowls shown in Figure 6 is when the user is using the clear lamp, that is the lamp 18^b, it will not show red at the side upon which the red light is. In other words, the reflector bowl 15 acts as a shield with relation 55 to the red light 18^b. If both these lamps 18^b were mounted in the same reflector, there would be a red reflection on the side toward the red lamp.

It will be understood, of course, that the 60 tension on the spring 24 holds the lens 21 in Figure 1 in its adjusted position on the rods 23. It will be seen that the base of the lantern is relatively wide so that the lantern will not easily tip over when set 65 on top of a car. It will be obvious, of

course, that this lantern is adapted for household use, for camping trips, and in a large number of other circumstances.

I claim:—

1. A lantern of the character described 70 comprising a battery containing case, a skeleton guard extending from one end of the case and adapted to support the same, an electric lamp disposed at this end of the case, a handle attached to the case, and a 75 lens carried by the case and disposed in front of and spaced from the electric lamp to thereby permit light rays to be directed laterally without interference from said lens. 80

2. In a railway lantern, a body having a handle, an openwork guard projecting downward from the lower end of the body and forming a base on which the body may be supported, an electric lamp carried by 85 the lower end of the body, means whereby the lamp may be electrically connected with or disconnected from a battery carried within the body, and a lens operatively supported upon the body in line with said lamp 90 and adjustable toward or from the lamp but being spaced therefrom to permit light rays to be directed laterally without interference from the lens.

3. In a railway lantern, a body having a 95 handle, an openwork guard projecting downward from the lower end of the body and forming a base on which the body may be supported, an electric lamp carried by the lower end of the body, means whereby 100 the lamp may be electrically connected with or disconnected from a battery carried within the body, a lens disposed below the lamp, and rods supporting said lens in spaced relation to the lamp with which rods the lens 105 has sliding frictional engagement, whereby the lens may be shifted toward or from the lamp and held in its adjusted position.

4. A railway lantern of the character described comprising a body adapted to contain a battery and having a handle, the lower end of the body being provided with a skeletonic guard constituting a base on which the body may rest, the lower end of the body carrying a metallic lamp socket, an 110 electric lamp disposed in said socket and having a base, a battery disposed within the body and having a laterally disposed contact, means for making or breaking the circuit through the battery and lamp comprising a pivotally mounted disk disposed in the lower end of the body and having an outwardly projecting handle and extending at right angles to the vertical axis of the body, the body being slotted to permit the 115 projection of the handle, said disk having a metallic connection with the lateral contact on the battery and in one position establishing a metallic connection between the central contact on the battery and the base of 120 125 130

the lamp, and in the other position disestablishing said connection.

5. A railway lantern of the character described comprising a body constituting a battery containing case, a skeleton guard extending from one end of the case and adapted to support the same, a plurality of differently colored electric lamps disposed in this end of the case, a switch whereby any

one of said lamps may be electrically connected to the battery or disconnected therefrom, and independent concave reflectors disposed behind and concentric to each lamp.

In testimony whereof I hereunto affix my signature.

PAUL GENESY.
